UNITED STATES PATENT OFFICE.

CHARLES BERNHARDT PETERSON, OF PERRYVILLE, MARYLAND.

FASTENING DEVICE.

1,413,489.

Specification of Letters Patent. Patented Apr. 18, 1922.

Application filed August 31, 1921. Serial No. 497,179.

To all whom it may concern:

Be it known that I, CHARLES BERNHARDT PETERSON, a citizen of the United States, and a resident of Perryville, in the county 5 of Cecil and State of Maryland, have invented certain new and useful Improvements in Fastening Devices, of which the following is a specification.

The present invention relates in general 10 to a driven fastening device such as nails, spikes and the like, and has for its object to provide a device of this character which is of simple and durable construction, reliable in operation and easy and inexpensive to 15 manufacture and which when in use is interlocked with the material with which it is associated whereby it is positively prevented from accidental displacement and firmly maintained and positioned to exert 20 its fastening action.

Other objects and advantages of the invention reside in certain novel features of construction, combination and arrangement of parts which will be hereinafter more 25 fully described and particularly pointed out in the appended claims, reference being had to the accompanying drawings forming part of this specification, and in which:

Figure 1 is a side elevational view of the 30 preferred embodiment of the invention positioned as in use, parts being broken away and shown in section for the sake of illustration;

Figure 2 is an end elevational view there- 35 of;

Figure 3 is a plan view;

Figure 4 is a detail view in section, illustrating the latch mechanism;

Figure 5 is a detail view of the latch and 40 associated spring;

Figure 6 is a plan view of a slightly modified form of the invention, especially adapted for use as a railway spike.

Referring to the drawings wherein for 45 the sake of illustration is shown the preferred embodiment of the invention and more particularly to Figures 1 to 5, inclusive, the numeral 10 designates generally a master nail or spike which includes a shank 50 11 having a four cornered point 12 and a head 13. The head 13 extends laterally from the shank for a substantial distance and it carries adjacent its outer end a guide nail or spike 14. For this purpose the head 13 55 is provided with a transverse opening 13^a, the axis of which is parallel to the axis of

the master shank 10 and the upper end of the opening 13^a is enlarged to provide a seat 13^b. The guide nail or spike 14 includes a shank 15 which snugly fits the opening 13^a and a head 16 which is snugly received on the seat 13^b so that when the shank 15 is received in the opening 13^a and the head 16 is received on the seat 13^b the guide nail 14 will extend in parallel relation to 65 the master nail. The shank 15 is provided with a guide opening 15^a which extends obliquely through the shank 15 of the guide nail or spike 14 and which is aligned with the opening 17 provided in the shank 11 of 70 the master spike 10.

A locking or cross spike 18 is provided and has a head 19 which is received in a cavity 20 provided therefor in the head 13 of the master spike 10, and a shank 21 which 75 extends through the guide opening 16 of the guide spike 14 and through the aligned opening 17 of the shank of the master spike, the opening 17 thus constituting a seat or bearing for the shank of the locking spike. The 80 cavity 20 includes an obliquely extending opening 20^a which slidably and snugly receives the shank 21 of the locking spike and a seat 20^b upon which the head 19 of the locking spike 18 is received. As shown in 85 Figure 1, the underside of the head 20 of the locking spike is a plane surface and snugly fits a similar plane surface of the seat 20^b formed in the cavity 20 and these plane surfaces are arranged at right angles 90 to the axis of the shank of the spike and of the openings 16 and 17 thus providing for a complete nesting of these parts in assembly.

Latching mechanism is provided for positively securing the locking spike in position, that is for interlocking it with the master spike and for this purpose a cavity 23 is provided in the shank 11 of the master spike and communicates with the opening 17 100 thereof. A swinging latch 24 is pivotally mounted in the cavity by means of the pivot pin 25 and is urged out into locking position by means of a bowed or bent blade spring 26. The shank 21 of the locking spike is provided with a locking shoulder 105 27 which engages the swinging latch 24 in the assembly to bring about the interlocking of the master spike and the locking spike.

In practice, with this form of the invention the master spike is first driven into the wood or other material and the guide spike

is then driven through its opening in the head of the master spike. When the guide spike is completely driven into the wood the interaction of the head of the guide spike and the seat provided therefor in the head of the master spike results in the disposition of the guide spike in parallel relation to the master spike with its guide opening 16 aligned with the opening 17. It is obvious that if desired the guide spike can be made integral or rigid with the master spike and in that event it would be driven simultaneously therewith. In either event the locking spike is next driven and it passes through the guide opening 16 and through the opening or bearing 17 until the latch 24 snaps into engagement with its shoulder 27. It is to be noted that the shank 21 of the locking spike is guided by the opening 20^a of the cavity 20 to insure its entering the guide opening 16. When this occurs the head 19 of the locking spike is completely nested in the cavity 20 provided therefor in the master spike and the head of the spike 25 presents a continuous and uninterrupted surface.

The embodiment of the invention shown in Figure 6 is identical in all respects with that shown in Figures 1 to 5 and above described except that the head of the master bolt is provided with laterally extending lugs 29 which are adapted to engage the base of the rail.

I claim:

35 1. A fastening device of the character described comprising a master spike including a shank and a laterally extended head, said head having an opening extending transversely therethrough and having a seat, a 40 guide spike having its shank extending through the opening and having a head received in said seat, the head of the master spike also having an obliquely extending opening and an obliquely disposed seat, the 45 shank of the guide spike and the shank of the master spike having obliquely extending openings alined with the obliquely extending opening of the head of the master spike, a locking spike including a shank extending 50 through said alined openings, and a head re-

ceived in the obliquely disposed seat, said shank of said master spike having a cavity therein communicating with the obliquely extending opening, a swinging latch pivotally mounted in said cavity, and a spring for 55 urging said latch to operative position, said shank of said locking bolt having a locking shoulder cooperable with said latch.

2. A fastening device of the character described comprising a master spike including 60 a shank and a laterally extended head, said head having an opening extending transversely therethrough and having a seat, a guide spike having its shank extending through the opening and having a head received in said seat, the head of the master spike also having an obliquely extending opening and an obliquely disposed seat, the shank of the guide spike and the shank of the master spike having obliquely extending 65 openings alined with the obliquely extending opening of the head of the master spike, a locking spike including a shank extending through said alined openings and a head received in the obliquely disposed seat, and 70 latch mechanism carried by the shank of the master spike and cooperable with the locking spike.

3. In a fastening device, a master spike including a head, a guide spike associated 80 with the head of the master spike and a locking spike carried by the head of the master spike and extending obliquely through the guide spike and the master spike, and latch mechanism for interlocking the master spike 85 and the locking spike.

4. In a fastening device, a master spike including a head, a guide spike associated with the head of the master spike and a locking spike carried by the head of the master 90 spike and extending obliquely through the guide spike and the master spike.

5. In a fastening device, a master spike including a head and a shank having obliquely extending and alined openings, a 95 locking spike extending through the openings of said head and shank and latch mechanism carried by the shank and cooperable with the locking spike.

CHARLES BERNHARDT PETERSON.
